UNITED STATES PATENT OFFICE.

AUGUST E. MUELLER, OF CHICAGO, ILLINOIS, ASSIGNOR OF ONE-THIRD TO THOMAS J. HRUBY AND ONE-THIRD TO JOHN O. HRUBY, JR., BOTH OF CHICAGO, ILLINOIS.

VALVE.

1,228,469.

Specification of Letters Patent.

Patented June 5, 1917.

Application filed June 17, 1916. Serial No. 104,152.

To all whom it may concern:

Be it known that I, AUGUST E. MUELLER, a citizen of Argentina, South America, and a resident of Chicago, in the county of Cook 5 and State of Illinois, have invented certain new and useful Improvements in Valves; and I do hereby declare that the following is a full, clear, and exact description thereof, reference being had to the accompanying 10 drawings, and to the characters of reference marked thereon, which form a part of this specification.

This invention relates to a novel valve for controlling the supply of steam or other motive agent from a steam boiler or other source to a plurality of engines. The valve has been designed more particularly for use in connection with the type of rotary motor shown in my co-pending application, Serial 20 No. 102,627, filed on the 9th day of June, 1916, and illustrated in connection with the power plant of a tractor in another application filed by me on the 12th day of June 1916, Serial No. 103,271.

25 In the rotary motor shown in the first-mentioned application, means are provided for delivering the motive fluid to either one or both sides of the axis of rotation of the rotor, the fluid being delivered to and against 30 one side of the rotor when operating the engine for moderate power, and being simultaneously delivered to the rotor on both sides of its axis of rotation when the maximum power is to be developed from the engine. 35 The engine is also provided with means for delivering motive fluid against one side of the rotor in a direction to reverse the rotation thereof.

The valve herein shown has been designed 40 as a simple expedient and readily controllable valve mechanism to control the flow of steam or other motive fluid from the source of supply to front and rear pairs of motors that are mounted on swinging axle stubs, 45 such as is shown in my later application, second above referred to. It will be understood, however, that the essential features of the valve may be embodied in a construction to control the delivery of a motive fluid 50 under other conditions of use and in connection with other types of engines.

In the drawings:—

Figure 1 is a partial vertical section and a partial side elevation of a valve embodying 55 my invention.

Fig. 2 is a section thereof on the line 2—2 of Fig. 1.

As shown in said drawings, 10 designates the main body of the valve casing herein shown as circular in cross section. It is provided with a central chamber 11 and with a plurality of passages 12, 12, 13, 13, 14 and 15, which lead radially outwardly through the casing from the central chamber and open at the outer side of the valve casing. Pipes 16, 16 are screw-threaded in the passages 12; pipes 17, 17 are screw-threaded in the passages 13; a pipe 18 is screw-threaded in the passage 14 and a pipe 19 is screw-threaded in the passage 15. In the above suggested use 70 of the valve in connection with the tractor referred to, it may be assumed that the pipes 16, 16, are directed to the front of the vehicle and are branched for connection with the inlet ports of the front engines and that 75 the pipes 17 are likewise directed toward the rear of the vehicle and are branched for connection with the rear engines. Also it may be assumed that the pipe 18 is directed toward the rear of the vehicle and is branched 80 for connection with the inlet reverse ports of the rear engines and that the pipe 19 is similarly directed toward the front of the vehicle and is branched for connection with the reverse inlet ports of the front engines. 85

22 designates a hollow rotative combined distributing and valve member which is seated in the recess 11. Said rotative member 22 is provided with oppositely disposed ports 23, 23. Said ports are adapted to alternately 90 register with the passages 12, 13, 14 and 15. In the position of the parts as shown in Fig. 2 the distributing and valve member 22 is in position to cut off motive fluid to all of the distributing passages. If the said member be turned in the direction indicated by the arrow so as to bring one of the ports 23 into register with the lower pipe 16 and the other port into register with the upper pipe 17, steam or other motive fluid may be directed through said pipes to the single ports of the engines for the development of moderate power. If the said valve and distributing member be rotated to bring the ports 23 (which latter, it will be observed, are 100 wider than the individual passages 12 and 13) into register with both pairs of passages steam or other motive fluid will be delivered through both pairs of pipes 16, 17 so as to deliver motive fluid against the rotors on 110

both sides of their axes of rotation to develop the higher power of the engines. To reverse the engines, the distributing and valve member 22 is further turned to bring 5 the ports 23 into register with the passages 14 and 15, whereupon steam or other motive fluid is directed to the reverse inlet ports of the engines.

I have herein shown a simple form of 10 construction for admitting steam to the distributing and valve member 22 and for actuating said member. The construction herein shown is as follows: 25 designates the inlet pipe for the motive fluid which leads 15 through a stuffing box 26 that is carried by an upper removable plate 27 bolted or otherwise fixedly secured to the casing 10. The said pipe 25 passes through a central opening in a cover plate 28 that is applied over 20 the open upper end of the distributing and valve member 22 and is secured thereto by screws 29 or other suitable fastening means. The pipe 25 is provided at its lower end with a flange 30 which fits beneath the cover 25 plate 28. The said removable plate 27 is recessed at 31 to receive the cover plate 28 and a suitable packing 32 is applied between the plate 27 and the casing 10. The construction described provides steam tight 30 joints between the several parts.

The valve member and distributing chamber 22 is provided with a stem 34 which extends downwardly through an opening in the casing 10 which leads from the chamber 35 11 and through a stuffing box 35 carried by the lower side of said casing 10. The construction is such that the said distributing and valve member 22 may be rotated on its axis relatively to the lower end of the pipe 40 25, the latter being held fixed from rotation through its connection with the steam boiler or other source of motive fluid. The stem 34 is herein shown as provided at its lower end with a gear wheel 36 by which it may 45 be rotated from any suitable control device, such, for instance, as is illustrated in the tractor construction above referred to.

The valve device shown constitutes an exceedingly simple, compact, inexpensive and 50 efficient device for distributing motive fluid from a central source of supply to a number of engines, both for forward and reverse operation thereof, and enables a number of engines to be controlled from a central point 55 with facility and accuracy.

I claim as my invention:—

1. A valve device comprising a casing 60 having a chamber and a plurality of radial passages leading therefrom; a rotative, ported, hollow distributing and valve member in said chamber provided with a stem which extends outwardly from said chamber and a supply pipe leading through the wall

of said casing and through one wall of said member and having a wide face bearing 65 with the inner face of said wall.

2. A valve device comprising a casing having a chamber and a plurality of radial passages leading therefrom; a rotative, 70 ported, hollow distributing and valve member in said chamber, and provided with a stem which extends outwardly from said chamber; a supply pipe leading through the wall of said casing and into said chamber and provided at its inner end with a flange; 75 a removable cover plate fastened to said member through which said pipe extends and bearing at its inner face against said flange, and means to rotate said valve and distributing member.

3. A valve device comprising a casing formed with a central chamber which is open to one side of the casing and provided with a plurality of radial passages leading therefrom; a hollow, rotative, ported distributing and valve member in said chamber and open at the open side of the chamber; a removable cover plate to cover the open side of said member and provided with a central opening; a plate applied over said 85 casing against said cover plate and provided with a stuffing box; a supply pipe extending through said stuffing box and said cover plate and having a face bearing against the inner side of said cover plate, and means for 90 rotating said distributing and valve member.

4. A valve device comprising a hollow casing provided with two oppositely disposed pairs of ports and with two oppositely disposed single ports and a hollow 100 rotative valve member in said casing provided with two oppositely disposed ports adapted to register with the ports of the casing.

5. A valve device comprising a casing 105 having a chamber; two oppositely disposed pairs of passages leading therefrom; two single, oppositely disposed passages leading from the chamber intermediate said pairs, and a hollow rotative valve and distributing 110 member, with means to supply motive fluid thereto and provided with oppositely disposed ports adapted to be brought alternately into register with the opposed pairs of passages and with the opposed single passages, said ports being made of a width to span the receiving ends of said pairs of passages, with means for rotating said member.

In testimony whereof, I have hereunto set my hand at Chicago, Illinois, in the presence 120 of two witnesses, this 14th day of June, 1916.

AUGUST E. MUELLER.
